W. P. FEENEY

STOCK REGULATOR

1,763,691

Filed Aug. 5, 1929

UNITED STATES PATENT OFFICE

WILLIAM P. FEENEY, OF MANISTEE, MICHIGAN

STOCK REGULATOR

Application filed August 5, 1929. Serial No. 383,446.

This invention pertains to improvements in regulators and more particularly to stock regulators for paper making machines.

In my Patents 1,134,831, granted April 6, 5 1915; 1,143,523, granted June 15, 1915, and 1,331,057 granted February 17, 1920, I have shown certain types and improvements in stock regulators for paper making machines.

This invention relates to certain improvements on these inventions and other improvements not disclosed in any of the above patents.

Previously there have been certain disadvantages in stock regulators such as permitting stratification of the pulp whereby settling takes place allowing a variation in density of the stock fed to the paper making machine. Also there has been a certain lag in the reaction of the control mechanism to changes in volume or characteristics of the feed stock.

One of the primary objects of my invention is to overcome the disadvantages stated above.

Other objects and advantages of my invention will become apparent from the following specification and drawings in which;

Figure 1 is a perspective view of my stock regulating apparatus, and

Figure 2 is a detailed view of the adjustable float portion taken after 2-2 of Figure 1.

Referring more particularly to the drawings in which like reference characters denote like parts, my device consists of a stock regulator 1 which may be a box of wood or metal or other suitable substance. This regulator 1 is divided into sections 2, 3, and 4 by means of the partitions 2' and 3'. The stock is admitted to the section 2 through the inlet pipe 5. There is an outlet line 6 from the overflow section 3 which returns the stock to the supply. The outlet 7 from the section 4 directs the stock to the paper making machine.

The regulating mechanism consists of a float 8 which may be spherical or any other shape. The spherical shape appears to be most suitable for this purpose. The float is connected by means of the adjustable rod 9 to the arm 10 which pivots at 11 on the bearings 11'. This arm 10 is preferably made of

aluminum or other light alloy so as to render the float as sensitive to variations in liquid level or density as possible. The gate 12 is also connected to the arm 10. A weight 13 adjustably movable on the arm 14 may be used to counterbalance the weight of the arm 10 the gate 12, and the float 8. A hand wheel 15 is connected to the threaded rod 19 permitting the float to be adjusted vertically. Thus the float may be regulated in such a manner as to permit the flow of the amount of the stock, desired at the paper machine.

There is an opening 16 between the sections 2 and 3 of the regulator box. At the bottom of this opening there is a lip 17. The gate 12 moves in this opening and may rest on the lip 17 in such a manner as to not allow any stock to flow from section 2 to section 3 under the gate 12. At the sides of the opening 16 there are placed the flanges or projections 18 and 19. These have an edge 20 which is curved to the arc of movement of the gate 12. Thus these flanges 18 and 19 also act as closure mediums to substantially stop any stock from flowing around the sides of the gate 12 into the overflow section 3, when the gate 12 rests on the lip 17. On the other side of the gate 12 and also fitting snugly against it without hindering its motion, there is the trough or apron 21, the forward part of which rests on the supporting bar 22. I have shown this trough as being adapted to pivot at the point 23 so that the forward edge may be lifted upon a vertical position. This operation will be described more in detail later.

In section 2 I have shown fillets 24 in the corners where the sides of the regulator box connect with the partition 2'. These fillets eliminate dead corners where there would be no circulation of the stock and thus a tendency for the stock to settle or separate.

The operation of my device is as follows:

Stock is pumped into the section 2 through the pipe 5. The stock fills the section 2 and flows over the gate 12 onto the apron 21 and into the section 4. The float 8 may be adjusted to such a position that when the feed stock entering through the pipe 5 is sufficient to take care of the amount required by the paper making machine, the gate 12 will

rest on the lip 17. Therefore, should the supply of stocks entering section 2 increase over that required by the machine, the float 8 will be lifted. This in turn lifts the gate 5 12 and permits an opening between the lower portion of the gate 12 and the lip 17. It is seen that the forward portion of the trough or apron 21 is above the lip 17 so that when the stock passes over the lip 17 it drops into 10 the chamber 3 and is returned to the stock pump or supply through the pipe 6. Stock, of course, may still pass over the upper portion of the gate 12 on to the apron 21 into the section 4 to the paper making machine. 15 Due to the opening between the gate 12 and the lip 17 the level of stock in chamber 2 is lowered and thus the float 8 again drops and closes the flow into the section 3. The flow of stock may be such that there is continually 20 an opening from section 2 into the section 3 and yet stock flowing over the gate continuously on to the apron 21. Such an operation would be brought about if the supply coming in through the pipe 5 was consistently 25 greater than the amount required for the paper making machine flowing out through the pipe 7. In such a case there would be a certain amount continuously recycled from the section 3. By adjusting the float 8 to the 30 proper position it is possible to obtain an even flow of any desired amount of stock to the paper making machine. If it is desired to eliminate the paper making machine completely from the circuit, either permanently 35 or temporarily, the trough of apron 21 may be lifted, pivoting about the rod 23. In this way any stock which flows either over or under the gate 12 drops into the overflow chamber 3 from which it would be returned 40 to the supply source.

My device is also sensitive to changes in density of the stock. If the stock becomes thick the float will tend to rest higher on the 45 stock and thus recycle a certain amount of the heavy stock. In this way the amount of solids to the paper making machine may be controlled.

It can therefore be seen that in my regulator stratification in the supply chamber 2 has been eliminated, and that there is always circulation through this chamber. Thus 50 there is no variation in the density of the stock which is permitted to flow through the paper making machine. Also I have a structure in which the bearings are positioned at such a point as to not be affected by water or stock. In this way I am able to use ball bearings and thus obtain a very sensitive control.

While I have disclosed only a specific form 55 of my invention and in connection with a specific use, it is obvious that there may be changes and improvements which might be made by one skilled in the art without departing from the spirit of the invention. I

therefore, wish to be limited only by the appended claims.

I claim:

1. A stock regulator comprising an inlet chamber, an overflow chamber, an outlet chamber, a float operating in said inlet chamber, a gate operated by said float between said inlet chamber and said overflow chamber, and a trough between said inlet chamber and said outlet chamber adapted to catch the overflow from said gate. 70

2. A stock regulator comprising an inlet chamber, an overflow chamber, an outlet chamber, a float operating in said inlet chamber, a gate operated by said float between said inlet chamber and said overflow chamber, and a trough between said inlet chamber and said outlet chamber adapted to catch the overflow from said gate, and a counter-balance adapted to balance said float and gate. 80

3. A stock regulator comprising an inlet chamber, an overflow chamber, an outlet chamber, a float operating in said inlet chamber, a gate operated by said float between said inlet chamber and said overflow chamber, and a trough between said inlet chamber and said outlet chamber adapted to catch the overflow from said gate. 90

4. A stock regulator comprising an inlet chamber, an overflow chamber, an outlet chamber, a float operating in said inlet chamber, a gate operated by said float between said inlet chamber and said overflow chamber, and an adjustable trough between said inlet chamber and said outlet chamber adapted to catch the overflow from said gate. 95

5. In a feed state regulator for a paper machine, a float, a gate operated by said float, said gate adapted to move to permit stock to flow under it to an overflow and adapted to move to permit stock to flow over it to said paper machine. 105

6. In a feed state regulator for a paper machine, a float, a gate operated by said float, a trough, said gate adapted to move to permit stock to flow under it to an overflow and adapted to move to permit stock to flow over it to said trough machine. 110

In testimony whereof, I have signed my name to this specification this 31st day of July, 1929. 115

WILLIAM P. FEENEY.
